UNITED STATES PATENT OFFICE.

F. R. WILLSON, OF COLUMBUS, OHIO.

IMPROVEMENT IN HARROWS.

Specification forming part of Letters Patent No. 79,042, dated June 16, 1868.

To all whom it may concern:

Be it known that I, F. R. WILLSON, of Columbus, Franklin county, Ohio, have invented certain new and useful improvements in Harrows; and I do hereby declare that the following is a full, clear, and exact description thereof, reference being had to the accompanying drawings, in which—

Figure 1 represents a plan view, and Fig. 2 represents a side view.

Like letters indicate like parts.

In the annexed drawings, A A represent two bars that are pivoted together at their front ends.

B B represent similar bars that are pivoted together at their front ends, and are arranged between the bars A A, and, being about of the same length of said bars, extend slightly to the rear thereof. The bars B B are each provided with a perforated metal plate at their rear ends, by which means they are connected together to operate at a suitable distance from each other. These plates are shown at D D in Fig. 1, and are connected by a bolt or pin, h.

Arranged on the under sides of the bars A and B are a series of grooved blocks, K K K. These blocks are pivoted at both ends to the rails A and B, respectively. The block at the forward part of the harrow, where the bars come together, is placed horizontally, so that the rails A A are pivoted to its front and the rails B B are pivoted to its rear end. The remaining blocks K K are placed diagonally inward from the rails A to the rails B. Within

the groove of each block K is secured a metal plate, C, which is divided in the center, and the front bent outward and the rear part bent inward, as shown. These plates are formed as described for harrow-teeth, and when arranged with the frame specified form a series of teeth that will effectually cut and break the clods, &c.

This device can readily be adjusted for operating in contracted or an enlarged manner, and can be changed so that the rails A and B may lie together at one side. The teeth can be readily removed from the grooved blocks whenever desired.

The device herein described is intended as an improvement upon my patent of September 24, 1867.

Having thus fully described my invention, what I claim as new, and desire to secure by Letters Patent, is—

The arrangement of the outer rails, A A, and inner rails, B B, and the grooved teeth-holding blocks K K, pivoted in the manner described, and the perforated bars D D, when the several parts are constructed and operating substantially as specified.

In testimony that I claim the foregoing I have hereunto set my hand this 16th day of March, 1868.

F. R. WILLSON.
